CLAIM

The ornamental design for combined tag and cord for bag containing moisturizing beads or the like, substantially as shown and described.

DESCRIPTION

FIG. 1 is a front elevational view of a combined tag and cord for bag containing moisturizing beads or the like, showing my new design;

FIG. 2 is a right elevational view thereof;

FIG. 3 is a top plan view thereof;

FIG. 4 is a rear elevational view thereof.

The cord has been shown fragmentally in FIG. 2 for ease of illustration.
